ERASER ATTACHMENT FOR PENCILS AND
THE LIKE

De Traville M. Alford, Nashville, Tenn.

Application January 2, 1937, Serial No. 118,712

3 Claims. (Cl. 120—38)

This invention relates to eraser attachments for pencils, pens, and the like, and has for its principal object the provision of an eraser having a plurality of erasing ends, each of which may 5 be of a different quality of erasing material or designed for different type of erasures.

A further object of this invention is the provision of an eraser for attachment to pencils, pens and the like, having a plurality of erasing ends 10 projecting outwards at right angles to the axis of the pen or pencil whereby said pen or pencil will be prevented from rolling when placed upon an inclined surface.

A further object of this invention is the provision of an eraser, for attachment to a pencil, pen or the like, of novel and useful shape and construction which will provide a relatively blunt erasing surface for general erasing and a sharp, bevelled erasing edge for detail work which will 20 permit erasing a character in closely written or printed work without marring the adjoining characters.

A further object of my invention is the provision of an eraser for attachment to a pencil, pen or the like, having a plurality of erasing ends, one of which is designed for coarse work 25 and one end for fine or detailed work, thus providing for economy and long life of the erasing material.

30 A further object of my invention is the provision of an improved form of means for attaching said eraser to a pencil, pen, or the like in a secure and rigid manner.

A further object of my invention is to provide 35 an eraser attachment for pencils, pens and the like which is striking in appearance, which is cheap and simple to manufacture and which is convenient and economical to use.

These and other objects which will later appear 40 are best understood by reference to the following specification taken in connection with the accompanying drawing in which:—

Figure 1 is a side elevation of a pencil showing my improved form of eraser and attachment 45 mounted thereon.

Figure 2 is a sectional view of the same taken along the line 2—2 of Figure 1 and looking in the direction of the arrows,

Figure 3 is a fragmentary sectional view of 50 the same taken along the line 3—3 of Figure 1,

Figure 4 is a fragmentary side elevation of a pencil showing my improved form of eraser attached thereto by an optional attachment means,

Figure 5 is a sectional view of the same taken 55 along the line 5—5 of Figure 4 and

Figure 6 is an enlarged perspective view of the eraser of my invention.

Referring now in more detail to the drawing the numeral 10 denotes a conventional lead pencil staff to the end of which, the eraser member 11 5 is attached. The eraser member 11, as shown in Figure 6, is made of rubber or other erasing material, and has a cylindrical portion 11a having a flat end 11b at right angles to the axis of the cylinder. Formed integrally therewith is the 10 portion 11c of square cross section and having one face 11d formed at right angles to the axis of the cylindrical portion 11a and a second face 11e forming an oblique angle with said axis thereby providing the sharp erasing edge 11f. 15

The pencil staff 10 is provided at one end with a depression 10a, the form of said depression being that of a section of a cylinder, the axis of said cylinder being at right angles to the axis of said pencil staff 10. A portion of the cylindrical part 11a of eraser 11 next adjacent the square portion 11c is received into the depression 10a and secured therein by the U-shaped strap member 12, the straight ends of which enclose a portion of the end of the pencil staff 10, being formed to fit closely there-around. Said ends of the U-shaped member 12 are enclosed and secured against the pencil staff 10 by a sleeve 13 which bears against the outwardly turned ends 12a of the U-shaped strap member 12. Indentations 20 13a serve to hold the parts more securely. 25

In the optional form of my invention as disclosed in Figures 4 and 5 the eraser member 11 is affixed to the end of the pencil staff 10 by means of the tubular sleeve 14 which in turn is secured to the pencil staff by crimping or indentations 14a, or by any other suitable means. The tubular sleeve 14 is provided with two tapered tongues 14b which are bent toward one another to enclose a part of the cylindrical portion 11a of eraser member 11 adjacent the face 11d. Indentations 14c may be used to further secure the eraser member 11 to the tapered tongues 14b. 35 40

It will thus be seen that I have provided an eraser attachment for pens, pencils and the like 45 wherein an eraser member having a flat end and a sharp end is mounted at its approximate center upon the end of a pen or pencil at right angles to the axis thereof, presenting two erasing surfaces, one for coarse work and one for delicate work, at the same time providing means whereby the pencil is prevented from rolling upon inclined surfaces, and forming an assembly of novel and striking appearance. 50

While I have shown and described certain 55

specific forms of my invention which, in practice, have been found to satisfactorily effectuate the stated purposes and objects thereof, it is manifest that the structural details may be considerably varied without involving any departure from the principle of my invention, and hence I do not limit myself to the device as shown, except to the extent indicated in the following claims.

10 I claim:

1. An eraser attachment for pencils, pens and the like, comprising a rubber eraser member having a cylindrical portion and a portion of square cross-section formed integrally and joined end to end therewith, the free end of said cylindrical portion being at right angles to the axis of the cylindrical portion and the free end of the portion of square cross-section forming an oblique angle with said axis, a pencil staff 15 having a groove formed in one end thereof to receive the cylindrical portion of said eraser member, a U-shaped strap member, having elongated ends with outwardly turned tips, said strap member partially encircling the cylindrical portion of said eraser member and the elongated ends of said strap member lying along the sides of said pencil staff, and a tubular sleeve 20 encircling said ends and the end of said pencil staff and abutting said outwardly turned tips.
2. An eraser attachment for pens, pencils and the like, comprising an eraser member of suit- 25

able erasing material, having a cylindrical portion and a portion of square cross-section formed integrally and joined end to end therewith, the free end of said cylindrical portion being at right angles to the axis of said portion 5 and the free end of the portion of square cross-section forming an oblique angle with said axis, a pencil staff having a groove formed in one end thereof to receive the cylindrical portion of said eraser member, a tubular sleeve for attachment to the end of said pencil staff, and tapered tongues on opposite sides of said sleeve and at one end thereof, said tongues being bent to enclose the central part of the cylindrical portion of said eraser member.

10 3. An eraser attachment for pens, pencils and the like, comprising an eraser member of suitable erasing material having a cylindrical portion and a portion of square cross-section formed integrally end to end therewith, the free 20 end of said cylindrical portion being formed at right angles to the axis thereof, and the free end of the portion of square cross-section forming an oblique angle with said axis, and means for supporting said eraser member upon the end 25 of a pencil staff, the axis of said staff being at right angles to and intersecting the axis of said eraser member substantially at the center thereof.

DE TRAVILLE M. ALFORD. 30
